UNITED STATES PATENT OFFICE.

JENETTA V. BOHANNAN, OF BALTIMORE, MARYLAND.

MACHINE FOR TAGGING PLUG-TOBACCO.

SPECIFICATION forming part of Letters Patent No. 634,321, dated October 3, 1899.

Application filed July 11, 1899. Serial No. 723,475. (No model.)

To all whom it may concern:

Be it known that I, JENETTA V. BOHANNAN, a citizen of the United States, residing at Baltimore, in the State of Maryland, have invented 5 certain new and useful Improvements in Machines for Tagging Plug-Tobacco; and I do declare the following to be a full, clear, and exact description of the invention, such as will enable others skilled in the art to which it applies 10 pertains to make and use the same, reference being had to the accompanying drawings, and to the letters of reference marked thereon, which form a part of this specification.

This invention relates to improvements in 15 tagging-machines designed especially for use in applying tags to plug-tobacco, and in carrying out my present invention it is my purpose to generally improve upon and render more efficient the machine for a like purpose 20 upon which I have been granted Letters Patent in the United States Patent Office, No. 628,746, July 11, 1899.

The improvements consist, first, in the provision of means for holding the tag in position 25 underneath the magnet-hammer when said tag has been fed out of the end of the feeding-trough, the means which I provide being recessed fingers which engage with the tag and hold it from turning after it has been pushed 30 out of the end of the trough, the fingers being withdrawn as the hammer depresses the tag against the plug of tobacco held adjacent thereto; secondly, another part of my invention consists in the provision of reciprocating 35 brushes, which are mounted one in each compartment of the magazine and made to contact with the upper edges of the push-plates in the magazines and provided for the purpose of brushing off tags which become entangled 40 with one another, thus causing the latter to fall back into the magazine, while other tags, which are picked up singly by the push-plates, are allowed to fall by gravity into the tilting receptacles, from which they fall 45 by gravity into the chutes leading to the magnet-hammers, and, thirdly, my improvements consist in the provision of means for holding tags in the slotted and tilting tag-receptacles as the latter swing from horizontal positions 50 to such positions as to allow the tags to slide into the upper ends of the receiving-chutes, with which said slotted receptacles are

brought into registration when swung to their highest limit.

My invention is clearly illustrated in the 55 accompanying drawings, which, with the letters of reference marked thereon, form part of this application, and in which drawings similar letters of reference indicate like parts throughout the several views, in which— 60

Figure 1 is a side elevation of my improved machine for tagging plug-tobacco, showing connected to the counter-shaft of the machine a crank which has connection with a pitman provided to reciprocate the slotted fingers which hold the tags in their proper position adjacent to the magnet-hammers after the tags have been pushed out of the lower ends of the chutes. Fig. 2 is a sectional view showing in side elevation the rack for retaining the tags in the slotted receptacles while the latter are being tilted up from a horizontal position. Fig. 3 is a top plan view of the slotted rack which is provided to hold the tags in proper position and adjacent to the 75 magnet-hammers. Fig. 4 is a vertical sectional view through the magazine, showing the manner in which the brushes contact with the faces of the push-plates when removing the tags which become entangled. Fig. 5 is a cross-sectional view through the rack for holding the tags in position in one of the slotted tag-receiving receptacles. Fig. 6 is a detail view of the magnet-hammer depressed and the slotted rack withdrawn, and Fig. 7 80 is a perspective view of the members for holding the tags in the slotted receptacles. 85

Reference now being had to the details of the drawings by letter, A designates the frame of the machine, having an operating-shaft B, 90 with driving-pulley B' thereon, and C is a counter-shaft mounted in suitable bearings in the frame, and at right angles to the shaft C is a geared wheel C', having teeth meshing with the beveled gear-wheel B''. At the opposite end of the shaft C is keyed a wheel C'', with counterbalance portion C'', and C' is a wrist-pin carried by said wheel, to which pin is pivoted the pitman C'', made up of two sections with turnbuckle connections, whereby 100 the pitman may be lengthened or shortened to limit its throw. A shaft D, mounted in bearings on the frame, has a crank D' at one end adjacent to said wheel C'', which crank is

pivoted to the end of the wrist-pin C⁴, whereby a rotary movement is imparted to said shaft D. To the shaft D is secured the cam D².

- 5   Mounted near the upper end of the frame of the machine is the magazine E, with inclined sides and open top and bottom. The longitudinal ends of said magazine are inclined, and this magazine contains a series of partitions E', disposed in directions parallel to the ends of the magazine, thus forming a series of compartments with inclined longitudinal walls, each of which compartments is divided by inclined partitions, which at 10 their upper ends are integral with or secured to the under faces of the partitions E' and have their lower edges free, with slight spaces intervening between said free edges and the upper faces of the partitions E'.
 15   E³ is a block having apertured ears E⁴, to which the upper end of the pitman C⁵ is connected, and secured to said block is a series of push-plates E⁵, disposed at angles corresponding to the inclinations of the partitions E' in the magazine. These plates are of such a width as to snugly fit into the spaces between the lower free ends of the partitions E² and E', and when said plates are at their lowest limit their upper edges are slight distances below the lower ends of the partitions E². When the plates are at their upper or highest limit, their upper edges extend a slight distance above the upper edges of the partitions E'. Each of said push-plates at 20 its upper end has a recessed portion E⁶, extending the entire length of the plate. Its recesses are provided to receive the tags from the compartments of the magazine and raise the same to positions from which they are deposited into the slotted and tilting tag-carrying receptacles. It will be noted that the upper edges of the partitions E' are preferably at acute angles to the upper inclined faces of said partitions, so as to allow the faces of the 25 tilting tag-receiving receptacles to come into contact with the said edges when in positions to receive the tags.
 30   Mounted in the bearings F at the upper end of the frame of the machine is a rock-shaft F', to one end of which is keyed a crank F², having a longitudinal adjusting-slot in which a pin connected with the bar F⁵ is adjusted. The bar F⁵ carries at its lower end an anti-friction-wheel F⁹ and has a longitudinal slot F⁷, in which a pin F⁸, carried by the frame of the machine, works in order to guide said bar in its reciprocating movements as the anti-friction-wheel rides upon the circumference of the cam-wheel D².
 35   Secured to the rock-shaft F' is a series of slotted receptacles H, which are in horizontal positions, as shown in Fig. 2 of the drawings, when at their lowest limit and are inclined at an angle, as shown in Fig. 1 of the drawings, when tilted up to allow the tags carried thereby to be deposited into the chutes. These 40 receptacles H have the slots H' therein, extend-
 45

ing their entire length, each receptacle being preferably L-shaped in cross-section, as shown in the drawings. The upper edges of the walls 70 of the receptacles are inwardly and downwardly beveled, as at h, on the outer faces of the walls of the receptacles, having the inclined upper edges, as described, and are designed to fit snugly against the beveled portion of the partitions E' when the receptacles are at their lowest limit or in positions to receive tags from the magazine. When in this position, the upper beveled edges h are about flush with the upper edges of the partitions 80 E', so as to allow the tags which are elevated by the push-plates to fall down into slots in said receptacles. The fixed ends of the receptacles H extend a slight distance in front of the rock-shaft F' and cover the slots in the receptacles. Near their fixed ends are the plates H², secured at their upper angled edges to the upper edges of the receptacles, and the outer ends of said plates H² are downwardly and outwardly inclined, slight spaces intervening 90 between the lower edges of said plates H² and the upper inclined edges of the short walls of the receptacles, the spaces being of sufficient width to allow the spurs of the tags to pass through in their course to the feeding-chutes. 95 These plates are provided to assist in retaining the tags in the slots when the receptacles are tilted up to their highest limit, in which position the tags slide into the chutes.

Pivoted to each of the receptacles is a bar 100 H⁴, said bar being pivoted at H⁵ and the outer end of each bar being fastened on its upper edge to a bar H⁶, and has an angled projection H⁷, the lower angled end of which projection extends below the under edges of the 105 plates H² for the purpose of preventing the tags from falling out of the slotted receptacles until the latter nearly reach their upper limit or in such positions that the lower ends of the slotted tag-receptacles are brought into 110 registration with the upper open ends of the feeding-chutes. These chutes I each have a slot I' to receive the spurs of the tags as they fall by gravity from the ends of the receptacles into said chutes. In order to allow the tags 115 to leave the receptacles and be fed into the chutes, the bar H⁶, when the receptacles rock to their highest limit, will strike against the guide-plates I², which plates are cut away or recessed on their edges, as at I¹. These 120 guide-plates are provided to guide the tags as they leave the receptacle and enter the upper ends of the chutes I. As the slotted receptacles approach their highest limit the bar H⁶ will strike the shoulders on the plate I² 125 and cause the bar H⁴ to be raised, so that the angled ends H⁷ thereof will be raised out of the paths of the spurs of the tags, thus allowing the latter to readily fall into the chutes, through which they are conveyed to positions 130 whence they are driven into the plugs of tobacco. These chutes are bent so that their lower ends are at right angles to their upper open ends, so that the tags will turn from

edge positions to flat or horizontal positions, with spurs downwardly disposed when they reach their lowest positions at the outlet ends of the chute.

5 Mounted on the brackets K of the frame is the shelf K', which supports the spring-actuated posts K², the lower ends of which posts work in sockets K³ on the shelf K'. Secured to said sockets K³ is a cross-bar K⁴, to which 10 cross-bar the lower ends of the chutes I are secured, each of these chutes being recessed away, forming spaces between their forward ends, through which the posts carrying the feeding-shoes work. Mounted on the cross- 15 piece L, which is apertured and carried on posts K², are the antifriction-rollers L', journaled on shafts above the spring-actuated posts K².

Reciprocating on the table K' underneath 20 the feeding-box L^x is the push-plate L², whereby the plugs of tobacco are pushed forward underneath the magnet-hammers n, where they receive the tags. Mounted on said push-plate and extending inward are the arms R, 25 the free ends of which are widened, as shown at R', and have an angled edge R², which is adapted when the said arms are thrown outward to strike against the antifriction-rollers and cause the magnet-hammers n to be depressed. 30

Mounted on the shaft S is a crank S', connected to the counter-shaft C^x by means of the rod S², and carried by said shaft S is an arm S³, which is pivoted to the tag-feeding shoe S⁴, whereby as the shaft is rocked the tags are pushed forward singly out of the end of each chute. Mounted on the shaft C^x is a cam T, and horizontally sliding in the framework of the machine is a bar T', which is bent 35 at right angles in two positions, as at T² and T³, respectively, and connected near its outer end to a rack T⁴, which rack is horizontally disposed and designed to reciprocate in suitable guideways on the shelf K'. This rack 40 has a series of slotted arms or fingers T⁵, one arm or finger for each magnet-hammer, and the slot in each arm being of sufficient width to receive the spurs of the tags as they are ejected from the ends of the chutes and hold 45 the tags from turning until they are in proper positions underneath the magnet-hammers to be depressed by the latter into the plugs of tobacco underneath. Secured to said bar T' is an angle-plate T⁶, against which the cam 50 T strikes at each revolution of the shaft C^x, thus causing the bar T' to be thrown outward or toward the rear of the machine and causing the rack secured to the end of said bar to be withdrawn from underneath the magnet- 55 hammers while the latter are being driven down to apply the tags to the plugs of tobacco. After the cam has passed the angled portion T⁶ the spring T⁷, which is mounted on the rod T⁸, secured at one end to the angled plate T⁶, its other end passing through an aperture in the frame of the casing, will 60 cause the bar T' to resume its normal posi- 65

tion or such a position as will cause the slotted rack-bar to be disposed underneath the magnet-hammers and in positions to receive 70 and hold the tags from turning after they have been forced out of the ends of the feeding-chutes.

Mounted in the end wall of each of the compartments of the magazine is a rod V, carrying a brush V', adjacent to the upper edges of each partition-wall, said rods passing through apertures in the angled plate W on the frame of the machine, and pivoted to an arm Y, carried by the frame of the machine, is a rod 80 Y', being pivoted at Y², the lower end of said rod Y' being disposed in the path of the ratchet-wheel X, having teeth X' about its circumference. The upper end of said rod Y' has a boxing Y³, having a loose pivotal 85 connection with the rod V, and bearing between the outer wall of the magazine and the inner face of said boxing Y³ is a spring Y⁴, which is provided to return the upper end of the rod Y' to its normal or vertical position 90 after the lower end of said rod has been tilted outward by each tooth of the ratchet-wheel, thus causing the brush to reciprocate as the shaft C^x rotates, this reciprocating of the brush (there being one in each compartment 95 of the magazine) causing the tags which become entangled to be brushed off from the upper edges of the push-plates and allowing the same to fall by gravity back into the compartments of the magazine. 100

The other part of my invention, which consists in means for holding the tags in the slotted receptacles while the latter are being tilted from horizontal to their highest positions, from which the tags are allowed to fall 105 into the chutes, consists of the bars J, mounted loosely upon the shaft F', said bars carrying a series of L-shaped members in cross-section J², one of said members being provided for each of said slotted receptacles. These bars are 110 held normally at an inclination, as shown in Fig. 2, by means of the rods J³, the lower free ends of which rest normally upon the brackets J⁴ on the frame of the machine. These members J² are connected together by means 115 of cross-pieces J⁵ and are adapted to be carried with the slotted receptacles as the upper edges of said receptacles strike against the short angled longitudinal edges of said members, which will cause the bars J, which are 120 journaled on the shaft F', to turn on their pivots and travel with the receptacles until they have reached their highest limit. When the upper edges of the receptacles strike against the members J², the lower longitudinal edges of the latter will be in alignment 125 with the strips H² to form a continuous slot, through which the spurs of the tags slide. When the tag-receiving receptacles return to their horizontal positions, the arms J³ will 130 come in contact with the brackets J⁴ and the members resume their normal position, returning by gravity thereto.

In operation when the machine begins to

operate the shaft C^X rotates simultaneously with the reciprocating movement of the pusher-plates, which raise the tags from the magazine and deposit the same into the slot-

5 ted tag-receiving receptacles. The ratchet-wheel upon said shaft C^X will cause the bar Y' to tilt upon its pivot Y^2 , causing the brush V' to reciprocate, with the free ends of its bristles against any tags that may become 10 entangled with one another, causing the same to fall back into the magazine. At each revolution of the shaft C^X the bar T' is reciprocated, holding the tags from turning and in 15 proper position underneath the magnet-hammers, and the said members J^2 will hold the tags from being thrown out of the slots by centrifugal force, which becomes great when the machine is operating rapidly.

Having thus described my invention, what 20 I claim to be new, and desire to secure by Letters Patent, is—

1. In a machine for tagging plug-tobacco, the combination with the feeding-chutes, the magnet-hammers and means for operating the 25 same, members adapted to hold the tags underneath said magnet-hammers, and means for withdrawing said members as the hammer is depressed.

2. In a machine for tagging plug-tobacco, 30 the combination with the frame, the chute, the magnet-hammers and means for operating the same, a reciprocating rack having slots or recesses therein, adapted to be held underneath said magnet-hammers to hold the 35 tags from turning, and means for operating the rack, as set forth.

3. In a machine for tagging plug-tobacco, 40 the combination with the magnet-hammers, the slotted tag-feeding chute, a rack having a series of recessed arms which recesses are adapted to register with the slots in the feeding-chutes, and a bar connected to said rack and a cam and operating-shaft on which the same is mounted for reciprocating the said 45 bar, as set forth.

4. In combination with a machine for tagging plug-tobacco, the magnet-hammers, the slotted feeding-chutes, a rack having slotted or recessed arms which are held in registration with the slotted chutes, and underneath the magnet-hammers, a bar working in suitable guides upon the frame of the machine, and connected with said rack, the operating-shaft and cam connected therewith, a plate 55 secured to, or part of said bar, against which said cam is adapted to strike to withdraw the rack from underneath the hammers and a bolt carried by said plate, and spring thereon |

for returning said rack to its normal position, as set forth.

5. In combination with the magazine made up of compartments, brushes having shank portions which work through apertures in the walls of the magazine and held adjacent to the partition-walls of the magazine, the operating-shaft and ratchet mounted thereon and a tilting bar connected at one end to the shank portion of one of the brushes its lower free end held in the path of the teeth of said ratchet - wheel, whereby the brushes are 70 pushed in, and a spring for returning the brushes to their normal position, as set forth.

6. In combination with the magazine of a machine for tagging plug-tobacco, brushes mounted to reciprocate in apertures in the 75 wall of the magazine, the apertured bracket in which the outer ends of the shank portions of the brushes work, the operating-shaft and ratchet-wheel keyed thereto, the bracket-arm secured to the frame and the bar pivoted 80 thereto, the lower free end of said bar disposed in the path of the teeth of the ratchet and the upper end of said bar having a loose pivotal connection with the shank portion of one of the brushes, and a spring for returning 85 the brushes to their normal position, as set forth.

7. In combination with the slotted tag-receiving receptacles the shaft on which the same are mounted, a rack having a series of 90 L-shaped members carried thereby, against which said receptacles are adapted to contact and be raised by said receptacles as the latter are thrown to their highest limit, thus forming continuous slots through which the 95 spurs of the tags carried by the receptacles are allowed to slide, as set forth.

8. In combination with the frame of a machine for tagging plug - tobacco, the shaft mounted thereon, slotted tag-receiving receptacles carried by said shaft, a series of L-shaped members and the bars J carrying the same and mounted upon said shaft and the arms connected to the said bars, the free ends of which are adapted to rest upon brackets 105 upon the frame and be held normally out of engagement with said receptacles, but designed to be raised by the latter to hold the tags in said receptacles, as set forth.

In testimony whereof I affix my signature 110 in presence of two witnesses.

JENETTA V. BOHANNAN.
